ELECTRIC SYSTEM.

1,301,080.

Specification of Letters Patent.

Patented Apr. 15, 1919.

Application filed May 21, 1915. Serial No. 29,525.

To all whom it may concern:

Be it known that I, JOHN L. CREVELING, a citizen of the United States, residing at Auburn, in the county of Cayuga and State of New York, have invented new and useful Improvements in Electric Systems, set forth in the annexed specification and drawing forming a part thereof.

My invention pertains principally to that class of electric systems wherein it is desired to maintain translating devices by means of a storage battery and a source of electrical potential difference wherein the source, at times, supplies current to the battery and, at times, to the translating devices, which devices are maintained by the battery when the said source is ineffective.

My invention has for a particular object, to provide means whereby a system as outlined above may be automatically operated.

In the drawing, Figure I. is a diagrammatic representation of an electric system, which is shown for the purpose of explaining one type of system falling within the scope of my invention.

Fig. II. is a diagrammatic representation of a portion of a modified system, which will be explained with reference to Fig. I. for the purpose of illustrating another concrete case falling within the scope of my invention.

In Fig. I., 1 represents a controllable source of electrical potential difference indicated as a generator provided with the field coil 2 having in series therewith a regulating resistance 3, which in this instance is indicated, for example, as of the carbon pile variety. The positive terminal of the generator is connected by the wire 4 with one terminal of the automatic switch indicated at 5, the other terminal of which is connected through a series coil 6, forming a part of said switch, with wire 7, and through a series coil 8 with the movable conducting lever 9, pivoted as at 10 and normally swung into the position shown in the drawing, as by adjustable spring 11, in which position the left hand extremity of the said lever 9 engages the first or zero resistance segment of the resistance device indicated at 12, for example, as of the ordinary sliding contact variety. The said zero segment is connected as by wire 13 with one terminal of the translating circuit regulat-

ing element 14, in this instance indicated as a carbon pile resistance, the before mentioned terminal of which is connected with the wire 15, which, branching at 16, may be adjustably connected with the low resistance shunt 17, and also with the shunt 18 having in series therewith the coil 19, for a purpose to be hereinafter described. The said shunts unite at the point 20, from which the wire 21 is led to the positive terminal of the storage battery 22, the negative of which is connected as by the wire 23 with the negative pole of the generator 1 and the negative terminals of the translating devices 24, the positive terminals of which are connected with the wire 25 having interpolated therein the switch 26, from which wire 27 is led to the second terminal of the translating circuit regulator 14, which terminal communicates as by wire 28 with the resistance device 29, provided beyond its highest resistance element with a blank segment 30, upon which rests the lever 9 when in the position shown in the drawing.

From the wire 15 is led the wire 31 to the adjustable resistance 32 connected with one brush of the meter armature 33, the opposite brush of which is connected as by wire 34 with the wire 21. The meter armature 33 is provided with a field by the permanent magnet 34 and is connected with the worm 34^a engaging a train of gears or metering mechanism, indicated at 35 as a high ratio reduction gear, which may rotate the friction disk or pinion 36 upon rotation of armature 33.

37 is an electro-magnet or solenoid in shunt across the storage battery 22 and tends to attract its armature 38 against the action of adjustable spring 39 so as to bring the friction disk or pulley 40 in operative contact with the friction pinion 36 so that when the motor armature 33 is revolving in a certain direction the frictional contact 36-40 will tend to swing lever 41 in a counter clockwise direction and upon sufficient motion cause the contact member 42 to bridge the contacts 46-47 and allow current to flow from wire 15 through wire 45, contact 46-42-47, wire 48 having in series therewith the solenoid or coil 49, and 105 through wire 50 to wire 23.

If the field of magnet 37 be at any time insufficient to cause operative contact at

36—40, then the spring 39 will swing the armature 38 away from the coil 37, the extent of such movement being limited by the adjustable stop 43, and allow the lever 41 to 5 return to the position indicated in the drawing, or brought into contact with its limiting stop 44, either by means of a spring, as indicated, or by gravity, as may be desired.

The solenoid 49 when excited is arranged 10 to draw the core 51 downwardly and swing the lever 9 in a counter clockwise direction so that the lefthand extremity of the said lever will first gradually increase the resistance indicated at 12 to a high value and 15 then engage the blank segment 52, breaking the circuit therethrough, while simultaneously decreasing the resistance through the device 29 from infinity, as is inserted by the blank circuit 30, to practically zero, as when 20 the lever 9 reaches the zero segment of the said device 29 indicated at 53.

54 is a dashpot, resisting too sudden movement of the lever 9.

The lamp regulator, in this instance indicated as comprising the carbon pile 14, is 25 regulated by movement of the lever 55, normally drawn in an upward direction as by adjustable spring 56, tending to increase the pressure upon the pile and decrease the resistance thereof.

57 is a voltage coil across the translating circuit as indicated, and tending normally to draw its core 75 downwardly and increase the resistance 14, while too sudden movement of the core is restrained by the dashpot 76.

The coil 8 is provided with a core 58 engaging the lever 59, whereby current in the coil 8 tends to cause the same to lift its core and swing the lever 59 to increase the resistance 3 and lower the voltage of the generator 1. Too sudden movement of the core 58 is restrained by the dashpot 60, while 40 the amount of current flowing in the coil 8 necessary to cause the same to move the lever 59 may be determined either by proportioning the parts so as to employ gravity for this purpose, or by an adjustable spring, as shown.

50 61 is a voltage coil across the translation circuit and provided with a core 62 engaging the lever 63 and tending to draw the same upwardly when excited, so as to increase resistance 3, while too sudden movement is restrained by the dashpot 64.

The automatic switch 5 is provided with a closing coil 65 in shunt across the generator 1, which coil is wound in such direction that it is assisted by the coil 6 when 60 current flows from the generator 1 through the said coil 6.

66 is a small coil opposing the action of coil 65 when excited, and is connected from the wire 4, as shown, with one of the contacts indicated at 67, the other contact 67,

being connected as indicated, with the wire 23. The said contacts 67 are electrically connected, when the lever 9 is in the position indicated in the drawing, in such manner as to connect the coil 66 across the generator. 70

The coil 66 is wound in such manner that when excited it opposes the coil 65 and thereby causes the closing voltage of the switch 5 to be a little higher when 66 has its circuit completed, for a purpose as will 75 hereinafter appear.

In Fig. II, like numerals are used to indicate like parts. And it will be noted that the metering mechanism of Fig. I. is omitted, while a voltage operated coil 69 across the battery 22 attracts, when sufficiently excited, the lever 70 and breaks contact between the same and the contact member 73 and establishes contact between the lever and contact member 72, thereby completing 85 the circuit through coil 49, which will then move the lever 70 across the surface of the resistance element 14 and perform the same function of gradually shifting the generator from the battery circuit to the translating 90 circuit as when the circuit of said coil was completed in the apparatus of Fig. I. by means of the metering mechanism. When the voltage across the battery 22 is insufficient to establish contact at 72 the contact 95 at 73 is made and completes the circuit through the coil 66 upon switch 5, as indicated, which performs the same function as will hereinafter be explained with regard to Fig. I.

100

An operation of my invention is substantially as follows: If the generator be at rest, or revolving below the critical speed, and the translating circuit switch 26 be closed, current will flow from battery 22 through wire 21 to point 20, where it will divide and part flow through shunt 17 to point 16, and part through coil 19 and shunt 18 to point 16, and thence through the wire 15, translating circuit regulating element 14, wire 110 27, switch 26 and wire 25 to the translating devices 24, from which return is made through wire 23.

105 And, I so adjust the spring 56 that, if the storage battery 22 have a voltage in excess of that desired upon the translating devices 24, current flowing through the shunt coil 57 across the translation circuit will cause the said coil to draw the core 75 downwardly so as to depress the lever 55 against 120 the action of spring 56 and increase the resistance 14 in such manner as to automatically hold the desired translating circuit voltage upon the translating devices in a well known manner. I preferably use a 115 translating circuit regulator which will hold this translation circuit voltage constant within very narrow limits, though details of construction of such delicately operating regulators are herein purposely omitted for 125 130

the sake of clearness, inasmuch as such regulators are now well known in the art.

5 A very small portion of the current flowing from the battery to the translating devices will flow around the shunts 17 and 18 through the wire 34, armature 33, variable resistance 32 and wire 31, and this current will cause the armature 33 to revolve, and I so connect the armature that this current 10 will revolve the same in such direction that the motion imparted through the worm 34^a to the train of gears 35 is such that if the disk 40 be brought in contact with the pinion 36 the motion imparted to 36 will 15 tend to revolve the disk 40 in a clockwise direction.

I so adjust the spring 39 that if the voltage of the battery 22 is at or above the normal working voltage of the battery, the 20 magnet 37 will hold the disk 40 in operative contact with the pinion 36. And if the voltage of the battery be below this or a pre-determined point, 37 will allow the spring 39 to break the contact between 40 and 36, 25 whereupon the lever 41 will return to the position shown in the drawing, regardless of what position it may have been in at the time 37 released its armature 38.

The coil 19 is so wound that current flowing from the battery through the said coil to the translating devices tends to slightly weaken the field set up by the magnet 74 and increase the speed of the armature 33 as the current through 19 is increased. I adjust 35 the proportion of the current desired to be sent through the coil 19 by adjustment of the shunts 17 and 18 with respect to each other; while I adjust the relative amount of current which shall go through the armature 33 by adjustable resistance 32, in a well known manner.

If now, the generator be brought to sufficient speed that its voltage is in excess of the normal translation circuit voltage, by an 45 amount which I determine by so proportioning the coil 65 that with one circuit through the coil 66 broken the said coil 65 will close the switch 5 at substantially or exactly the translation circuit voltage and 50 with the coil 66 energized as it is when the contact 67 is made, the current in coil 66 by opposing the coil 65 will require the desired excess over the translation circuit voltage to close the switch. When the switch 5 55 closes, current will flow from the generator 1 through wire 4, switch 5, holding coil 6, wire 7, solenoid 8 and wire 7 to the lever 9, and thence through wire 13, regulating element 14, wire 27, switch 26 and wire 25 to the translating devices; and if in excess of 60 the amount used in the translating devices, the remainder will flow through wire 15 to the point 16, where it will divide and part flow through shunt 17 to the point 20, and 65 part through shunt 18 and coil 19 to the

point 20 (a very small portion flowing through wire 31, resistance 32, armature 33 and wire 34), and thence through 21 to the storage battery, and return through wire 23 to the generator.

This charging current flowing into the storage battery will cause current to flow through the armature 33 in the reverse direction to that of the current flowing from the battery to the translation circuit, as described above when the generator was inactive, and therefore will cause the armature 33 to revolve in a reverse direction and revolve the disk 40 in a counter clockwise direction and eventually cause contact member 80 70 to cause electrical communication between the contact members 46 and 47, whereupon current will flow from wire 15 through wire 45, contact 46—42—47, wire 48 to coil 49, from which return will be made 85 through wire 50.

And, it will be noted that the portion of the charging current which flows through the coil 19 will be in the reverse direction to that described when the batteries were supplying the translating devices, and thus will tend to slightly strengthen the field of the magnet 74 and cause the armature 33 to revolve slower when a given current is being supplied to the battery than when the same 95 current is being taken therefrom.

The energization of coil 49 will draw the core 51 downwardly and swing the lever 9 against the action of dashpot 54 in a counter clockwise direction, gradually inserting 100 resistance at 12, bringing the same to a high value, and then to infinity, if desired, as when the lever reaches the blank segment 52, and simultaneously decreasing the resistance at 29 from infinity when the lever is on the 105 blank segment 30 to practically zero when on the segment 53, under which conditions the generator will be connected in effect across the translation circuit instead of across the battery circuit as before. The 110 revolution of the lever 9 will break the contacts at 67 and cut out the coil 66. Throughout the operation of the generator its shunt field coil 2 is in series with the resistance 3, and therefore the generator voltage may be 115 controlled by regulating the said resistance.

And, I so adjust the core 58 and other instrumentalities coöperating with the coil 8, that when the maximum desired output is reached by the generator any increase of 120 current through the coil 8 will lift the core 58 and increase the resistance 3 in such manner as to prevent this maximum current from being exceeded, and in this way I protect the generator from overload.

I so adjust the core 62 and instrumentalities coöperating therewith, that if at any time the voltage across the translation circuit very slightly exceed that voltage which the coil 57 and the coöperating regulating 130

element 14 are adjusted to hold upon the translation circuit, the coil 61 will, in a sense, usurp the function of regulating the translation circuit by increasing resistance 5 3 and preventing the generator voltage from exceeding this said voltage maximum, which is very slightly, and preferably unnoticed (i. e. in lamp intensity) in excess of the normal translating circuit voltage. And 10 therefore, when the lever 9 is swung throughout its range in a lefthanded direction, as above mentioned, the generator will supply the translating devices at constant voltage, while the coil 57 will cause the resistance 14 to be greatly increased, and thereby prevent back discharge from the storage batteries to the translating devices, except through a very high resistance rendering such discharge negligible. Thus it 15 20 will be seen that so long as the generator continues to run under these conditions it will simply supply the translating devices, while the battery may be held at its fully charged voltage, or a voltage considerable 25 in excess of that supplied by the generator, but restrained by the resistance 14 from materially discharging to the generator and translating circuit.

Now, if the generator slow down until its voltage fall below that sufficient to supply the translation circuit, the coil 61 will allow the resistance 3 to be withdrawn and the generator will supply its highest voltage for its speed of revolution. Simultaneously, 35 coil 57 will allow spring 56 to withdraw resistance 14 and feed the translating devices from the battery as the load falls off from the generator. And if the generator stop, switch 5 will open and back discharge will 40 be prevented thereby.

If now, the generator be started up again immediately, or before sufficient current has been supplied by the battery to materially affect the position of the lever 41, coil 49 45 will remain energized as before, and the generator will remain connected on the translation side of the regulator 14, while coil 66 will remain inoperative. And as soon as the generator reaches the translation 50 circuit voltage, coil 65 will close the switch 5 and cut in the generator without altering the translation circuit voltage or causing a jump therein.

Then if the generator speed be increased, 55 coil 57 will increase the resistance 14 and in effect cut out the storage battery, while the translation circuit will be regulated by coil 61, as above mentioned. If, however, the generator slow down or stop and remain 60 inactive for an appreciable length of time, the current flowing to the translating devices will cause the armature 33 to revolve and break the contact at 46-47 and allow the spring 11 to return the lever 9 to the 65 position shown in the drawing. And it will

be obvious that the armature 33 and its co-operating parts, operating as a meter to measure the current charge and discharge, as above described, will throw the generator connections from the battery circuit to the 70 translation circuit when the battery is charged.

Further, it will be noted that the current passing to and from the battery through the coil 19 as above pointed out, will, in an 75 adjustable manner, cause a greater current to pass through the battery in charging than is taken from it in discharging, and that by properly adjusting the portion in the coil 19 the inefficiency of the battery may 80 be quite closely anticipated and compensated for. However, should the meter mechanism get out of phase, so to speak, with regard to the condition of the battery, the ultimate result will be that the battery at some time 85 will fall below its normal operating voltage, whereupon the magnet 37 will release the armature 38 and the meter will immediately be reset automatically to allow a full charge to be given to the battery, and the 90 metering operation will be begun over again.

An operation of the modification intended to be brought out in Fig II, is substantially the same as that of Fig. I., with the exception that the connection of the generator 95 with the battery circuit or with the translation circuit is determined by the voltage of the battery 22 through the instrumentality of the coil 69, rather than through the metering mechanism shown in Fig. I. That is, 100 when the battery becomes charged until its voltage has risen to a predetermined maximum, which may represent its charged 105 voltage, 69 will attract the lever 70 against the adjustable spring 71 and break the contact 73 through the coil 66 of switch 5 and complete the circuit through contact 72 and coil 49, whereupon the said coil will lift its core and swing the lever 70 across the carbon pile 14, having preferably a brush contact therewith, and in that way gradually transfer the generator connection 7 from the battery circuit side of the member 14 to the translation circuit side thereof.

And, if the battery be now discharged 115 until its voltage drop below this predetermined maximum, the parts may return to the position shown in the drawing, whereupon the generator circuit will be connected with the battery circuit and the coil 66 120 will be in circuit for the function described with regards to Fig. I.

I do not wish in any way to limit myself to any of the exact constructions nor modes of operation described above in this 125 specification for the purpose of giving examples or illustrations of employment of my invention, for it will be obvious that wide departure from the above may be made without departing from the spirit and 130

scope of my invention, which is as set forth in the following claims:

1. The combination with

1. The combination with a source of electrical potential difference, a storage battery circuit and a translation circuit, of automatic means for connecting the source with the battery circuit under certain conditions and with the translation circuit under other conditions.

10 2. The combination with a source of electrical potential difference, a storage battery circuit and a translation circuit, of automatic means for connecting the source with the storage battery circuit during charging and with the translation circuit upon cessation of charging.

15 3. The combination with a source of electrical potential difference, a storage battery circuit and a translation circuit, of automatic means for connecting the source with the storage battery circuit during charging and with the translation circuit upon cessation of charging.

3. The combination with a source of electrical potential difference, a storage battery circuit and a translation circuit, of means for connecting the source with the battery circuit and with the translating circuit, and automatic means for determining which of said connections shall be made.

4. The combination with

4. The combination with a source of electrical potential difference, a storage battery circuit and a translation circuit, of means for connecting the source with the battery circuit and with the translating circuit, and means for determining which of said connections shall be made, depending upon the condition of the battery.

5. The combination with a source of electrical potential difference, a storage battery circuit and a translation circuit, of means for connecting the source with the battery circuit and with the translating circuit, and means for determining which of said connections shall be made, depending upon the amount of current supplied to the battery.

6. The combination with a source of electrical potential difference, a storage battery circuit and a translation circuit, of means for connecting the source with the battery circuit and with the translating circuit, and means for determining which of said connections shall be made, depending upon the amount of current supplied by the battery.

50 7. The combination with a source of electrical potential difference, a storage battery circuit and a translation circuit, of means for connecting the source with the battery circuit and with the translating circuit, and means for determining which of said connections shall be made, depending upon the amount of current supplied to, and by the battery.

55

8. The combination with a source of electrical potential difference, a storage battery circuit and a translation circuit, of automatic means for connecting the source with the battery circuit and with the translating circuit, and automatic means for determining which of said connections shall be made.

9. The combination with a source of electrical potential difference, a storage battery, a battery circuit, translating devices and a translation circuit, of a regulator between the battery circuit and the translation circuit, and automatic means for connecting the source of electrical potential difference upon opposite sides of said regulator affected by the storage battery. 70

10. The combination with a source of electrical potential difference, a storage battery, a battery circuit, translating devices and a translation circuit, of a regulator between the battery circuit and the translation circuit, and automatic means for connecting the source of electrical potential difference upon opposite sides of said regulator affected by the condition of the storage battery. 75

11. The combination with

11. The combination with a source of electrical potential difference, a storage battery, a battery circuit, translating devices and a translation circuit, of a regulator between the battery circuit and the translation circuit, and automatic means for connecting the source of electrical potential difference upon opposite sides of said regulator affected by the current delivered to, and taken from said battery. 85 90

12. The combination with a source of electrical potential difference, a storage battery, a battery circuit, translating devices and a translation circuit, of a regulator between the battery circuit and the translation circuit, and automatic means for connecting the source of electrical potential difference upon opposite sides of said regulator affected in different degree by current delivered to the battery and by current taken from the battery. 95 100

13. The combination with a source of electrical potential difference, a storage battery, a battery circuit, translating devices and a translation circuit, of a regulator between the battery circuit and the translation circuit, and automatic means for connecting the source of electrical potential difference upon opposite sides of said regulator affected by the condition of the storage battery, and means affecting the same in response to a condition of the battery. 110

14. The combination with a source of electrical potential difference, a storage battery, a battery circuit, translating devices and a translation circuit, of a regulator between the battery circuit and the translation circuit, and automatic means for connecting the source of electrical potential difference upon opposite sides of said regulator affected by the current delivered to, and taken from said battery, and means affecting the same in response to a condition of the battery. 125

15. The combination with a source of electrical potential difference, a storage battery, a battery circuit, translating devices and a translation circuit, of a regulator between the battery circuit and the translation circuit, and automatic means for connecting the source of electrical potential difference upon opposite sides of said regulator affected by the current delivered to, and taken from said battery, and means affecting the same 125

15. The combination with a source of electrical potential difference, a storage battery, a battery circuit, translating devices and a translation circuit of a regulator between 130

- the battery circuit and the translation circuit, and automatic means for connecting the source of electrical potential difference upon opposite sides of said regulator affected in 5 different degree by current delivered to the battery and by current taken from the battery, and means affecting the same in response to a condition of the battery.
16. The combination with a source of electrical potential difference, a storage battery, a battery circuit, translating devices and a translation circuit, of automatic means for connecting the said source with the battery circuit and with the translating circuit, of a 10 main switch in circuit with the said source and means for altering the adjustment of said switch, in accordance with which circuit the source is connected with.
17. The combination with a source of electrical potential difference, a storage battery, a battery circuit, translating devices and a translation circuit, of automatic means for connecting the said source with the battery circuit and with the translating circuit, of a 15 switch in circuit with the said source and automatic means for altering the adjustment of said switch, depending upon which circuit the source is connected with.
18. The combination with a source of electrical potential difference, a storage battery, a battery circuit, translating devices and a translation circuit, of automatic means for connecting the said source with the battery circuit and with the translating circuit, of a 20 automatic switch in circuit with the said source and automatic means for altering the adjustment of said switch, depending upon which circuit the source is connected with.
19. The combination with a source of electrical potential difference, a storage battery, a battery circuit, translating devices and a translation circuit, of regulating means uniting the battery and translation circuits, means for connecting the source with the 25 battery circuit under certain conditions and with the translation circuit under other conditions, and means for controlling the source.
20. The combination with a source of electrical potential difference, a storage battery, a battery circuit, translating devices and a translation circuit, of regulating means uniting the battery and translation circuits, means for connecting the source directly 30 with the battery circuit under certain conditions and directly with the translation circuit under other conditions, and means for controlling the source to each of said circuits.
21. The combination with a source of electrical potential difference, a storage battery, a battery circuit, translating devices and a translation circuit, of regulating means uniting the battery and translation 35 circuits and serving to divide one from the
- other, means for connecting the source with the battery circuit under certain conditions and with the translation circuit under other conditions, and means for controlling the said source when connected with the translation circuit responsive to voltage fluctuations in the translation circuit. 70
22. The combination with a source of electrical potential difference, a storage battery, a battery circuit, translating devices and a translation circuit, of regulating means for connecting the battery and translation circuits, automatic means for controlling said regulating means to substantially prevent discharge from the battery, 75 and automatic means for controlling the said source of electrical potential difference actuated by voltage fluctuations across the translation circuit. 80
23. The combination with a source of electrical potential difference, a storage battery, a battery circuit, translating devices and a translation circuit, of a regulator interposed between the battery circuit and the translation circuit, means for operating 85 the same in response to voltage fluctuations across the translation circuit and to substantially cut off the battery, and means for regulating the said source responsive to voltage fluctuations across the translation 90 circuit. 95
24. The combination with a storage battery, translating devices, and a controllable source of electrical potential difference, of means for charging said battery from said source against minor extraneous opposition, and means for supplying the translating devices from said source against regulative opposition, means for terminating the charge to the battery and supplying the translating 100 devices directly from said source and opposing discharge of said battery thereto. 105
25. The combination with a storage battery, translating devices, and a controllable source of electrical potential difference, of means for charging the battery from said source, means for regulating the charge by regulating said source, means for supplying the translating devices from said source, and regulating the voltage upon said translating devices by opposing the flow of current from the source thereto while charging the battery, and means for supplying the translating devices from said source at a lower voltage than that of the battery and 110 regulating the voltage upon said translating devices by regulating said source and opposing discharge of the battery thereto. 115
26. The combination with a generator, storage battery circuit and translation circuit, of means for connecting the generator under certain conditions with the battery circuit and under other conditions the translation circuit, combined with means whereby the generator is controlled in re. 125 130

- sponse to current fluctuations only when connected with the battery circuit and in response to voltage fluctuations when connected with the translation circuit.
- 5 27. The combination with a generator, storage battery and storage battery circuit, translating devices and a translation circuit, regulating means connecting the battery circuit and the translation circuit, 10 means for connecting the generator with the battery circuit to charge the battery at gen- erator voltage, means for preventing the generator current from exceeding a predetermined limit, means causing the generator to be connected with the translation circuit 15 to impress generator voltage thereupon and causing cessation of battery charge, and means for governing the generator in response to voltage fluctuations across the translation circuit when the generator is 20 connected thereto.

JOHN L. CREVELING.
